UNITED STATES PATENT OFFICE.

THOMAS CAPPARELLA, OF NEW YORK, N. Y., ASSIGNOR OF ONE-THIRD TO LEWIS H. GREVE, OF NEW YORK, N. Y.

DISPENSING MACHINE.

Application filed December 31, 1923. Serial No. 683,782.

To all whom it may concern:

Be it known that I, THOMAS CAPPARELLA, a citizen of the United States, residing at New York city, in the county of New York 5 and State of New York, have invented new and useful Improvements in Dispensing Machines, of which the following is a specification.

This invention relates to dispensing machines and more particularly to a tooth pick or match dispenser.

One of the principal objects of the invention is the provision of a tooth pick dispenser wherein a single tooth pick may be 15 ejected upon each operation of the machine in a highly sanitary manner.

Another object of the invention is to provide a tooth pick dispenser which includes an agitator operable on each operation of 20 the dispensing mechanism to prevent the jamming or clogging of the tooth picks in the container so that the operator is assured a tooth pick on each operation.

A further object of the invention is to 25 provide a tooth pick dispenser which is simple in construction, cheap of manufacture and highly efficient for the purpose intended.

With these and other objects in view, the 30 invention resides in certain novel construction and combination and arrangement of parts, the essential features of which are hereinafter fully described, are particularly pointed out in the appended claims, and are 35 illustrated in the accompanying drawing, in which:—

Figure 1 is a perspective view of my invention with a portion of the end wall broken away to show the operating mechanism.

Figure 2 is a vertical sectional view on the line 2—2 of Figure 1.

Figure 3 is a fragmentary rear elevation.

Figure 4 is a detail perspective view of 45 the agitator mechanism.

In public eating establishments such as restaurants it is the usual practice to provide a tooth pick receptacle for accommodation of the patrons which receptacle usually 50 exposes the tooth picks to the fingers of the persons removing the same from the receptacle. This has proven to be very unhealthy, as diseases may be easily transmitted from one person to another. It is therefore my 55 intention to provide a dispenser which is

primarily intended for use in dispensing tooth picks but it is to be understood that the same may be constructed for dispensing matches if desired without in any way departing from the spirit of the invention. 60

Referring more particularly to the drawing, the reference numeral 10 designates my invention in its entirety and which includes a receptacle of hopper 11, to which is applied a removable cover 12, which in the 65 present instance is shown as having a transparent glass window whereby the contents of the receptacle may be viewed without removing the cover so that the contents may be watched and the supply replenished 70 when it is exhausted. Legs 13 support the receptacle and may be of any suitable design which will add to the attractiveness of the device.

The receptacle is provided with an inclined outer bottom 14 and with an inclined inner bottom 15, which inner bottom is inclined at an angle greater than the outer bottom for a purpose to be presently described. The inner bottom 15 extends below and beyond the bottom of the receptacle to provide a trough 16, the center of the trough being cut-away as at 17 to provide a finger slot whereby a tooth pick may be easily removed after being ejected from 85 the receptacle. The wall 18 overlies a portion of the bottom 15 and is spaced therefrom to provide a passage 19 for permitting the tooth picks to gravitate singly to the ejecting roller 20. An inclined wall 21 rises 90 from the wall 18 whereby to cause the contents of the receptacle to gravitate in a direction toward the point where the passage 19 opens to the receptacle. The dispensing roller 20 is rotatably mounted in 95 the end walls of the receptacle at the lower end of the passage way whereby to close the same, and the roller is provided with a longitudinal groove 22 of a size to snugly receive a tooth pick designated at A. 100

The mechanism 23 is provided for operating said roller and comprises a gear 24 mounted on one end of the roller for meshing engagement with a gear segment 25, formed on a lever 26, the lever being pivoted 105 to the end wall of the receptacle as at 27. The mechanism 23 is enclosed in one end wall of the receptacle and one end of the lever projects through a slot 28 in the front wall of the receptacle and the other end of 110

the lever 26 has connected thereto one end of a spring 29, the other end of said spring being attached to a stationary part whereby to hold the projecting end of the lever in an upward position so as to bring the groove 22 of the roller in register with the passage way 19. A stop 30 limits the downward movement of the lever and the upper portion of the slot 28 serves to limit the upward movement as will be readily understood.

In order to prevent the tooth picks from becoming jammed about the entrance of the passage way 19 which would stop the flow of tooth picks to the roller, I provide an agitating means 31 which includes a rocker arm 32 pivoted as at 33 to a bracket supported by the bottom 14. One end of the rocker arm is formed with a head 34 and the other end is adapted to co-act with a pin 35 carried on the inner side of the segment 25, whereby movement of the segment in one direction will cause the rocking of the arm 32 so as to bring the head 34 against the bottom 14 where a slight tap is imparted. This will agitate the contents of the receptacle upon each operation of the lever 26 to provide an uninterrupted flow of tooth picks to the roller.

When it is desired to eject a tooth pick from the receptacle, the lever 26 is depressed which causes the segment 25 to move the gear 24 which is keyed to one end of the roller 20. The movement of the roller will cause the tooth pick which has been previously picked up by the groove 22 to fall by gravity into the trough 16. It will be of course understood that the spring 29 returns the lever to its normal position after the same has been released. Also on each operation of the lever, the agitator means is operated in a manner previously described.

In the present instance, the receptacle is shown as constructed of metal, but it will be understood that the same may be constructed of glass or other material without departing from the spirit of the invention.

What is claimed as new is:—

1. A dispensing machine comprising a receptacle having an inclined bottom, a wall spaced from said bottom and adapted to overlie a portion of said bottom, the space between the wall and the bottom constituting a passage, a roller mounted at the lower end of said passage, a groove in said roller for register with said passage, and operating means for oscillating said roller, and an agitator means operable by said operating

means, said agitator means including a rock arm pivoted beneath said receptacle for striking contact therewith.

2. A dispensing machine comprising a receptacle having an inclined passage, one end of which opens into the interior of said receptacle, a roller mounted at the other end of said passage for closing the same, a groove in said roller for the reception of a single tooth pick and normally held in register with the passage, a trough mounted in said roller, manually operable means for moving said groove out of register with the passage to eject the tooth pick and into said trough, and automatic means for moving said roller to said normal position upon the releasing of said manually operable means, and means operable by said manually operable means for agitating the contents of said receptacle, said means including a rock arm pivoted beneath said receptacle for striking contact therewith.

3. A dispensing machine comprising a receptacle having an inclined passage, one end of which opens into the interior of said receptacle, a roller mounted in the other end of said passage for closing the same, a groove in said roller for the reception of a single tooth pick, a gear keyed to one end of said roller, and an operating lever pivoted to said receptacle, a gear segment carried by said lever and movable therewith and adapted to mesh with said gear, means for holding said lever in an upward position to bring the groove in said roller into register with said passage, means for limiting movement of said lever in either direction, and an agitating means operable by said segment for striking contact with the exterior portion of said receptacle.

4. A dispensing machine comprising a receptacle having an inclined bottom, a wall adapted to overlie a portion of said bottom, to define a passage, a roller mounted at the other end of said passage, a groove in said roller for register with said passage, operating means including a gear segment for rotating said roller, an agitator means operable by said gear segment and including a rocker arm pivoted beneath said inclined bottom, a head formed on one end of said rocker arm for contact with said bottom, and a pin carried by the segment for co-action with the other end of said rocker arm.

In testimony whereof I have affixed my signature.

THOMAS CAPPARELLA.
